UNITED STATES PATENT OFFICE.

PHILIP WUEST, JR., OF PHILADELPHIA, PENNSYLVANIA, ASSIGNOR TO OSCAR BLASIUS, OF
"PHILADELPHIA, PENNSYLVANIA.

AUTOMATIC-PLAYING PIANO.

No. 906,355.

Specification of Letters Patent.

Patented Dec. 8, 1908.

Application filed April 20, 1908. Serial No. 427,964.

To all whom it may concern:

Be it known that I, PHILIP WUEST, Jr., a citizen of the United States, residing at Philadelphia, county of Philadelphia, and State of Pennsylvania, have invented a new and useful Improvement in Automatic-Playing Pianos, of which the following is a full, clear, and exact description, reference being had to the accompanying drawings, which form a part of this specification.

My invention relates to certain mechanism whereby the treadles, which operate the pneumatic mechanism when the piano is used as an automatic player, are normally concealed and out of action, and when desired for use, may be automatically moved into operative position.

In carrying out my invention, I form a recessed portion in the front frame which is normally closed by a cover. The treadles are hinged so as to be movable into and out of the recessed portion. When in the recessed portion the treadles are locked but are under the action of a spring tending to throw them outward, which, when the lock is released, throws them outward on their hinge. The cover, likewise, is hinged and, when in its closed position, is locked and acted upon by a spring tending to force it out, so that when the lock is released it is forced outward. The means for releasing the treadles and cover locks are connected together so that the locks may be simultaneously released. Further, the spring on the cover is not strong enough to cause the cover, when the lock is released, to move outward the full extent. The part to which this spring is connected, however, is movable and in line of movement of the treadles in swinging outward, so that the treadles in swinging outward throw this spring again into action, moving the cover to its full open position. This arrangement prevents the cover from moving outward with too much force and also prevents the treadles moving outward with too much force, as this cover spring, in being thrown again into action by the treadles, acts as a buffer to restrain the too rapid movement of the treadles.

I connect the mechanism by which the locks are released to the slidable shelf which carries the expression levers for the automatic piano-player. By this arrangement, the piano may be turned from an ordinary

playing piano into a condition for acting as a self-playing piano automatically and by merely pulling out the slidable shelf. The arrangement is such that neither the cover nor the treadles can move out too rapidly. The treadles are used to operate the bellows mechanism for the pneumatic portion of the instrument. The detailed mechanism by which this result is produced and which details also form part of my invention, will be more clearly seen by reference to the embodiment of my invention shown in the accompanying drawings. This embodiment I will now describe.

In the drawings: Figure 1 is a front view of my improved piano with treadles in operative position. Fig. 2 is a cross section with treadles in operative position. Fig. 3 is a cross section showing parts in closed position.

a is the piano.

b is a recess or opening in the case normally closed by the cover *c*. In this recess the treadles *d* for operating the piano automatically normally rest. These treadles are hinged to links *e* which are pivotally connected to treadle connector *x* within the recess. The treadles are also connected to the rod *f*. The rod *f* at each end has a head *g* and a pad *h*. At each end of rod *f* is an arm *y* pivoted to a bracket *i* connected to the piano frame.

j is a vertical rod connected at its lower end to a lever *k*, the other end of the lever *k* having a projection *l* which normally rests in a socket *m* on the interior of the cover *c*. The upper end of the rod *j* has an overhanging portion *n* resting on a horizontal arm *s* of a rod *o*, which rod *o* is connected at its upper end to a cord *p*, extending to the slidable frame *q*, carrying the expression levers for automatic playing. When the slidable frame is moved outward, through the medium of the cord *p*, the rod *o* is lifted. When the slidable frame is moved inward, the cord *p* being slack, the weight of the rod *o* will cause it to move downward.

r are leaf springs. Normally, the arms *y* rest against the springs *r* and are held locked there by the rod *f*, being held by the arm *s*. The cover *c* is also closed and held closed by the projection *l* resting in the socket *m*.

t are springs, one end connected to the cover *c*, the other end pivoted to levers *z*.

The strength of these springs *t* is not sufficient, when lock *l* and *m* are released, to throw the cover completely open.

In operation, when the shelf or frame *q* is pulled out, the rod *o* and rod *j* are elevated, releasing the treadles and the cover. The springs *r* force the treadles outwardly. The springs *t* force the cover *c* outwardly and upwardly, but are not sufficient in strength to move the cover to full open position. In the outward movement of the treadles the arms *y* strike the levers *z*, throwing the springs *t* again into tension and, with the further outward movement of the treadles, the cover opens to full open position. By this arrangement, the cover is prevented from moving too rapidly and springs *t* act as buffers to prevent the too sudden movement of the treadles. The inward movement of the treadles restores the parts to the closed position, and the cover locked against and compressing the leaf springs. The cover can then be released from the catch *w*, which retains it in its outward position, and closed, and locked in its closed position.

Having now fully described my invention, what I claim and desire to protect by Letters Patent is:—

1. In a self-playing piano, in combination, a recessed frame, a hinged cover, treadles pivotally mounted, independent of the cover, to swing within and without said recess, a locking mechanism within the recess for holding the treadles within the recess, a spring active in the closed position of said treadles and acting on said treadles to force them outward, and means to release the locking mechanism.

2. In a self-playing piano, in combination, a recessed frame, a hinged cover, a treadle pivotally mounted, independent of the cover, to swing within and without said recess, a spring against which said treadle rests in its inner position, a lock to hold said treadle in its inner position, and means to release said lock.

3. In a self-playing piano, in combination, a recessed frame, a cover, a treadle pivotally mounted, independent of the cover, to swing within and without said recess, a spring against which said treadle rests in its inner position, a lock to hold said treadle in its inner position, a movable shelf and connection between said lock and said shelf.

4. In a self-playing piano, in combination, a recessed frame, a hinged cover, a treadle pivotally mounted, independent of the cover, to swing within and without said recess, a spring against which said treadle rests in its inner position, a movable arm adapted, in one position, to hold said treadle in its inner position and means to move said arm out of locking engagement.

5. In a self-playing piano, in combination, a recessed frame, a cover, a treadle pivot-

ally mounted, independent of the cover, to swing within and without said recess, a spring against which said treadle rests in its inner position, a movable arm adapted, in one position, to hold said treadle in its inner position, a movable shelf and connection between said arm and said shelf.

6. In a self-playing piano, in combination, a recessed frame, a hinged cover, a treadle pivotally mounted, independent of the cover, to swing within and without said recess, a spring against which said treadle rests in its inner position, a rod connected to said treadle, a lock coacting with said rod in the inner position of the treadle and means to release said lock.

7. In a self-playing piano, in combination, a recessed frame, a cover, a treadle pivotally mounted, independent of the cover, to swing within and without said recess, a spring against which said treadle rests in its inner position, a rod connected to said treadle, a lock coacting with said rod in the inner position of the treadle, a movable shelf and connection between said arm and said shelf.

8. In a self-playing piano, in combination, a recessed portion adapted to receive the treadle, a hinged cover for said recess, a spring acting on said cover to move it outward, a hinged treadle movable on its hinge into and out of said recess, a spring acting to force said treadle outward, a lock for said cover when closed, a lock for said treadle when in the recessed portion, and means to simultaneously release said locks.

9. In a self-playing piano, in combination, a recessed portion adapted to receive the treadle, a hinged cover for said recess, a spring acting on said cover to move it outward, a treadle movable into and out of said recess, a spring acting to force said treadle outward, a movable part to which said cover spring is connected, and means adapted to operate said movable part in the outward movement of the treadle.

10. In a self-playing piano, in combination, a treadle, a recessed portion of the piano adapted to receive the treadle, a hinged cover for said recess, a spring acting on said cover to move it outward, a spring acting to force said treadle outward, said cover spring not being of strength sufficient to move the cover fully outward, a movable part to which said cover spring is connected, and means adapted to move said movable part, in the outward movement of the treadle whereby said cover spring is again rendered active to move the cover and also acts as a buffer to the movement of the treadle.

11. In a self-playing piano, in combination, a treadle, a recessed portion of the piano adapted to receive the treadle, a hinged cover for said recess, a spring acting on said cover to move it outward, a hinged treadle

movable on its hinge into and out of said recess, a spring acting to force said treadle outward, a lock for said cover when closed, a lock for said treadle when in the recessed portion, a rod controlling the cover-lock, a rod controlling the treadle-lock, said rods being connected to move in unison to release said locks, a 20

5 portion, a rod controlling the cover-lock, a rod controlling the treadle-lock, said rods being connected to move in unison to release said locks.

12. In a self-playing piano, in combination, a treadle, a recessed portion adapted to receive the treadle, a hinged cover for said recess, a spring acting on said cover to move it outward, a hinged treadle movable on its hinge into and out of said recess, a spring 15 acting to force said treadle outward, a lock

for said cover when closed, a lock for said treadle when in the recessed portion, a rod controlling the cover-lock, a rod controlling the treadle-lock, said rods being connected to move in unison to release said locks, a 20

slidable shelf and connection between said rods and said slidable shelf.

In testimony of which invention, I have hereunto set my hand, at Philadelphia, on this 17th day of April, 1908.
